DEVICE FOR POURING PREDETERMINED SERVINGS OF LIQUID

James Ernest McPhee, Culver City, Calif.

Application May 10, 1952, Serial No. 287,114

5 Claims. (Cl. 222—416)

1

This invention relates to dispensing devices for pouring predetermined quantities or servings of liquid from containers such as bottles.

One object of the invention is to provide a simple structural arrangement to prevent any inaccuracy in the dispensing operation that might arise from the formation of a liquid meniscus. Such a dispensing device includes an air tube for counterflow of air from the atmosphere into the bottle when the bottle is tipped to pour a serving of the liquid and there is a tendency for residual liquid in the air tube to form a meniscus that cuts off the flow of air through the tube. I have found that such blockage by a liquid meniscus inside the air tube occurs at the outer end of the air tube and I have further discovered that such blocking can be prevented by simply mounting a suitable transverse element across the inner end of the air tube. In the operation of the invention, any liquid meniscus in the air tube seeks the inner end of the air tube when the device is tipped to pouring position and there the liquid meniscus is diverted to one side by the transverse element, leaving the space on the other side of the transverse member free for the passage of air into and through the air tube.

A further object of the invention is to provide a construction for a dispensing device of this type that makes the device extremely economical to manufacture. The structure of the device is necessarily relatively complex as required by the particular automatic measuring operation that it performs and the structure includes a relatively large number of cooperating elements that have heretofore been separately fabricated. The invention reduces the total number of parts to a bare minimum and reduces the labor of fabrication and assembly by at least half.

A further object of the invention is to reduce the structure to a minimum number of one-piece assembly members that are adapted for frictional engagement with each other each of said members combining several of the cooperating elements of the device. Thus assembly labor is reduced to the simple procedure of bringing together complementary parts that are dimensioned for forced fit one with another.

A special feature of the invention is incorporation of the meniscus diverting element in a structural member that is separate from the air tube but is dimensioned to receive the air tube with a forced fit with the meniscus element serving as a stop for the tube in the assembly procedure. By virtue of this arrangement it is

2

necessary merely to cut the air tube to length from tubular stock and to force the cut tube into place against the meniscus diverting element.

The various objects and advantages of the invention will be apparent in the following detailed description, considered with the accompanying drawings.

In the drawings, which are to be regarded as merely illustrative,

10 Fig. 1 is a side elevation of the preferred embodiment of the invention;

Fig. 2 is a longitudinal sectional view of the device as mounted on a bottle in pouring position;

15 Fig. 3 is a longitudinal sectional view of a one-piece multiple-element member that provides part of the structure of the device shown in Figs. 1 and 2;

Fig. 4 is a transverse section taken as indicated by the line 4—4 of Fig. 3; and

20 Fig. 5 is a longitudinal sectional view of a second one-piece multiple element member included in the structure of the device.

The principal parts of the dispensing device shown in the figures include the following: a dispensing chamber 10 having a vent tube 11 and a pouring tube 12 which is extended by a pouring spout 13; a neck tube 15 which supports the dispensing chamber and is embraced by a resilient sleeve 16 to fit into the mouth of a bottle 17; an air tube 20 that extends through the neck tube into the dispensing chamber, the lower or outer end of the air tube being pinched or flattened as indicated at 21 for restricted flow; a meniscus diverting element 25 positioned across the inner end of the air tube; and a siphon tube 26 that communicates with the inner end of the air tube 20.

25 The siphon tube 26 surrounds the pouring tube 12 to provide an automatic siphon in which the down-leg is the pouring tube and the up-leg is the annular space between the pouring tube and the surrounding siphon tube. The neck tube 15 has a transverse end wall 27 across its inner end and has an opening 28 in its side near the end wall to provide communication between the neck tube and the interior of the dispensing chamber. The neck tube 15 is also formed with a suitable hood or guard 33 at the side opening 28 to serve 30 as a baffle to divert flowing liquid away from the inner end of the vent tube 11.

35 When the bottle 17 with the dispensing device mounted in the manner shown is tipped to pouring position as indicated in Fig. 2, liquid from the 40 bottle passes through the neck tube 15 and the

opening 28 into the dispensing chamber 10 and liquid in the dispensing chamber rises toward the inner end of the pouring tube 12. Air to replace the liquid poured out of the bottle enters the dispensing chamber 10 through the vent tube 11 and also enters the dispensing chamber through the pouring spout 13. When the liquid level rises to the edge of the siphon tube 26 surrounding the pouring tube 12, communication between the vent tube 11 and the air space in the tipped bottle is cut off and thereafter air enters through the pouring spout 13 alone.

When the liquid pouring into the dispensing chamber 10 rises above the level of the inner end of the pouring tube 12, the two legs of a siphon are completed or automatic siphon flow and siphon action is initiated with the liquid flowing upward through the siphon tube 26 around the pouring tube 12 and then downward through the pouring tube. This dispensing flow through the pouring tube 12 continues until the liquid level drops below the rim of the downwardly tipped siphon tube 26 whereupon siphon flow ceases and the liquid level in the tipped dispensing chamber rises to repeat the siphon cycle.

The restriction of the outer end of the air tube 20, created by pinching the end of the air tube as shown, minimizes the amount of liquid that enters the air tube. Liquid unavoidably enters the air tube 20 but the transverse element 25 across the inner end of the air tube prevents any blockage by liquid that would prevent one pouring cycle from following the previous pouring cycle without prolonged time delay and without change in the quantity of liquid dispensed in the second pouring cycle.

There is reason to believe that any liquid entering the restricted outer end of the air tube 20 that would ordinarily tend to block air flow therethrough is diverted to one side by the transverse element 25. Thus the liquid shifts to one side of the element 25 with the other side of the element providing a clear space for free air flow from the pouring spout through the air tube into the air space in the tipped bottle.

Preferably the meniscus diverting element 25 is positioned to divide the inner end of the air tube 20 into two unequal portions. Thus, as may be seen in Fig. 2, the element 25 is positioned off center with respect to the axis of the air tube 20, the element being positioned above the axis to provide a relatively large space below the element to receive a liquid meniscus when the device is tipped to pouring position and to provide a smaller space above the element for the free flow of air into the air tube.

In the preferred practice of the invention the parts to be separately fabricated for assembly comprise three cast or molded multiple element members in addition to the pouring tube 12 and the air tube 20.

The first molded or cast multiple element member, generally designated 35, forms the upper part of the dispensing chamber 10 when the dispenser is in its upright or non-dispensing position and includes as elements both the vent tube 11 and the pouring spout 13. The inner end of the pouring spout 13 is enlarged to form a seat 36 which is dimensioned to receive the pouring tube 12 with a forced fit.

The second multiple element cast or molded member is generally designated 40 and is best shown in Fig. 3. The second or lower member 40 mates with the first member 35 to complete the dispensing chamber 10 and is formed with a

neck 41 which constitutes a portion of the previously mentioned neck tube 15. The neck 41 is enlarged internally to form an annular seat 42 to receive the third member with a forced fit as will be explained. Preferably the second member 40 is also suitably formed to engage an intermediate portion of the air tube 20 thereby to serve as holding means to retain the air tube in assembled position. For this purpose, the second member 40 may be formed, for example, with an inner sleeve 44 dimensioned to embrace the air tube 20 in a suitably snug manner.

The third cast or molded multiple element member, generally designated 50 in the drawings, is best shown in Fig. 5. The member 50 has a tubular base portion 51 dimensioned to be inserted with a forced fit into the previously mentioned annular seat 42 of the second member 40. Above the base portion 51 the third member 50 provides a circular wall 52 together with the end wall 27 and hood 30 which combined with the second member 40 complete the neck tube 15 of the device. Integral with the end wall 27 and the hood 30 is a restricted tubular portion 53 of the third member 50 which is dimensioned to embrace the end of the air tube 20 with a forced fit. The previously mentioned siphon tube 26 is integral with the tubular portion 53 and both are integral with the transverse meniscus diverting element 25.

The manner in which the device may be manufactured and assembled will be readily apparent from the foregoing description. In preparation for assembly a supply of pouring tubes 12 are cut to length from stock tubing and a supply of air tubes 20 is provided by cutting lengths of smaller tubing to size and pinching the ends as indicated at 21. The three multiple element members 35, 40 and 50 are cast or molded, preferably being die cast and pouring tube 12 is mounted in the seat 36 in member 35. Member 50 is assembled to member 40 by forcing its base portion 51 into the annular seat 42. The vent tube 29 is then passed through the inner sleeve 44 of member 40 and is forced into the restricted tubular portion 53 of member 50, the air tube being forced home against the transverse meniscus diverting element 25. The first member 35 is then bonded to the second member with the pouring tube 12 extending into the siphon tube 26 as shown. The resilient sleeve 16 is then mounted on the neck 41 to complete the assembly.

My description herein of the presently preferred practice of the invention will suggest to those skilled in the art various changes, substitutions and other departures from my disclosure that may be made within the scope and spirit of my appended claims.

Having described my invention, I claim:

1. A liquid dispenser of the character described for use on a bottle, said dispenser having: a dispensing chamber; a tube connected with said chamber and adapted to seat in a sealed manner in the mouth of the bottle both to support the chamber and to provide a passage for flow of liquid from the bottle into the chamber when the bottle is tipped; a pouring tube mounted in said chamber for discharge flow therefrom, the inner end of said tube extending inward to the interior of the chamber; a vent tube mounted in said chamber for communication with the atmosphere, the inner end of said tube extending to a point above the inner end of said pouring tube when the chamber is tipped into pouring posi-

tion; an air tube extending through said neck tube for passage of air from said chamber into the bottle when the bottle is tipped, the outer end of said air tube having a restricted opening to minimize the entrance of liquid from the bottle; a continuous wall inside said chamber connected with the inner end of said air tube circumferentially thereof, said wall enclosing the inner portion of said pouring tube to cooperate therewith to form a pouring siphon; and an element mounted on said continuous wall end extending across the inner end of said air tube to divert any liquid meniscus at the entrance of the air tube to one side to avoid blocking air flow through the air tube.

2. A liquid dispenser as set forth in claim 1 in which said element abuts the inner end of said air tube and divides the entrance of said air tube into two unequal portions, the larger portion being the lower portion when the liquid dispenser is tipped to its pouring position.

3. In a liquid dispenser of the character described, the combination of an upper shell member, a lower shell member adapted to be bonded to said upper shell member to form a dispensing chamber, a tubular extension carried by said lower shell member to serve as a neck tube, and an integral siphon tube member having a portion extending into the upper shell member and an opposite portion thereof extending through the lower shell member and into the said tubular extension to hold said siphon tube member in assembled position in said tubular extension, and an air tube extending through said neck tube into said siphon member, a web member positioned across the end of said air tube, said end being that end extending into the said siphon tube member.

4. In a liquid dispenser of the character described, the combination of an upper shell member, a lower shell member adapted to be bonded to said upper shell member to form a dispensing chamber, a tubular extension carried by said lower shell member to serve as a neck tube, and an integral siphon tube member having a por-

tion thereof extending through the lower shell member and into the said tubular extension to hold said siphon tube member in assembled position in said tubular extension, and an air tube extending through said neck tube into said siphon member, a web member positioned across the end of said air tube, said end being that end extending into the said siphon tube member, said web being a thin piece of metal whose length is substantially equal to the internal diameter of said air tube and whose thickness is substantially less than the diameter of said air tube.

5. In a liquid dispenser of the character described, the combination of an upper shell member, a lower shell member adapted to be bonded to said upper shell member to form a dispensing chamber, a tubular extension carried by said lower shell member to serve as a neck tube, and an integral siphon tube member having a portion thereof extending through the lower shell member and into the said tubular extension to hold said siphon tube member in assembled position in said tubular extension, and an air tube extending through said neck tube into said siphon member, a web member positioned across the end of said air tube, said end being that end extending into the said siphon tube member, said web being a thin piece of metal whose length is substantially equal to the internal diameter of said air tube and whose thickness is substantially less than the diameter of said air tube, said web being positioned off center from the central axis of said air tube.
